Attorney

UNITED STATES PATENT OFFICE.

EARL G. S. TRACY, OF COKATO, MINNESOTA.

PEDAL SWITCH.

Application filed May 2, 1923, Serial No. 557,926. Renewed June 15, 1925.

To all whom it may concern:

Be it known that I, EARL G. S. TRACY, a citizen of the United States, residing at Cokato, in the county of Wright, State of Minnesota, have invented certain new and useful Improvements in Pedal Switches; and I do hereby declare the following to be a full, clear, and exact description of the invention, such as will enable others skilled in the art to which it appertains to make and use the same.

This invention relates to new and useful improvements in automobile signaling devices, and particularly to means for operating front and rear signals.

The principal object of the invention is to provide a circuit closing means carried by the brake pedal or the clutch pedal, for lighting front and rear lamps on the right or left side of the automobile, to indicate a change of direction.

The circuit closing means is so arranged that it will not operate during the ordinary use of the pedal, but requires a lateral or sidewise movement of the foot, of the operator, to accomplish the closing of one or the other of the circuits.

Another object is to provide a device of this character which is simple in construction, and which can be readily applied to the clutch or brake pedal of any of the automobiles now in use.

Other objects and advantages will be apparent from the following description when taken in connection with the accompanying drawing.

In the drawing:

Figure 1 is an elevation of a clutch pedal equipped with the improved circuit closer, viewed from the side.

Figure 2 is a rear elevation of the same.

Figure 3 is a vertical longitudinal sectional view through the pedal and the circuit closer, on the line 3—3 of Figure 2.

Referring particularly to the accompanying drawing, 10 represents the stem, and 11 the foot-piece of the clutch pedal of an automobile. This foot-piece is formed with the side flanges 12, which prevent the foot of the operator from slipping from the pedal. Formed vertically through the intermediate portion of the foot-piece, and adjacent the front and rear edges of the foot-piece, are the openings 13, and disposed through these openings are the legs of the yoke 14, the bight portion 15, of which extends trans-

versely of the foot-piece. An elongated plate 16 is disposed on the foot-piece 11, and has a central depending angular lug 17 which rests on the upper face of the foot-piece, the bottom face of said lug being of sufficient width to maintain the plate in a position with its ends spaced from the upper face of the foot-piece. Through the said lug 17 is disposed the said bight portion of the yoke, whereby the plate is mounted for lateral pivotal movement, by the sides of the foot of the operator. The arms or legs of the yoke extend below the foot-piece and are threaded to receive thereon the nuts 18, coil springs 19 being engaged on the said legs, and bearing against the lower face of the foot-piece and against the nuts, to hold the plate 16 in its normal position, but yieldable under pressure by the side of the operator's foot.

A push-button circuit closer 20 is mounted in each end of the foot-piece, directly beneath an end of the plate 16, so that when the operator rocks the plate, in either direction, by a lateral pressure of his foot, the lowered end of the plate will depress the adjacent push-button, and close the circuit. The device is adapted for use with a front and rear lamp, on each side of the automobile, one push-button controlling the lamps at one side of the automobile, while the other push-button controls the lamps at the other side. The arrangement of the lamps, and the wiring may be done in any desired and conventional manner, neither the lamps nor the wiring being shown.

In the ordinary use of the pedal, the plate 16 will not be rocked, the lateral movement of the operator's foot being necessary to depress either end of the plate for closing the proper circuit to light the appropriate set of signal lamps.

The device may be readily attached to the ordinary pedal of an automobile by simply boring several holes in the foot-piece to accommodate the arms of the yoke, and the push-button circuit closer. Furthermore, the driver does not need to use either hand to operate his direction signals.

What is claimed is:

1. In a circuit closing device for an automobile signal, the combination with the foot-piece of a control pedal, of a spring pressed yoke mounted on the foot-piece, a foot-plate mounted on the bight of the yoke and normally held against the foot-piece

by said yoke with its ends spaced from the foot-piece, said foot-plate being rockable against the tension of the spring pressed 10 against the yoke, and a circuit closing means on the 15 foot-piece beneath each end of the foot-plate for operation by said end upon lateral rocking of the foot-plate by the side of the foot 20 of the operator.

2. In a circuit closer for an automobile signal, the combination with the foot-piece of a control pedal, of a yoke having its arms 10 slideable vertically through the foot-piece

and its bight extending transversely thereof, a rockable plate on the bight of the yoke and having a lug resting on the foot-piece, 15 springs on the arms of the yoke for yieldably maintaining the rockable plate with its ends above the foot-piece, and circuit closing means on the foot-piece beneath each end of the rockable plate, for actuation by said end upon rocking of said plate.

In testimony whereof, I affix my signature.

EARL G. S. TRACY.
